Atty.

UNITED STATES PATENT OFFICE

FRITZ KOCKS, OF DUSSELDORF, GERMANY

ROLLING MILL

Application filed December 14, 1929, Serial No. 414,186, and in Germany March 7, 1929.

My invention relates to rolling mills and more especially to mills on which blanks are expanded. It has particular reference to a rolling mill which is adapted for the carrying out of the process described in my copending application for patent, Ser. No. 343,781, filed February 15, 1929, which comprises imparting to the blank equal feed velocity at all points of contact between the 10 rollers and the blank.

It is an object of my invention to improve the rolling mill by which the aforesaid process is carried out. To this end I arrange the axes of the rolls of the mill at an angle to the 15 axis of the blank which does not exceed 30 degs.

It has been found that a mill of the kind referred to is improved by inclining the axes of the rolls at a comparatively small angle to 20 the axis of the blank, as is shown but not claimed in the copending application.

In mills of this type the inclination of the axes of the rolls is large, and as a rule the angle which according to the present invention 25 must not exceed 30 degs., is about 60 degs.

Rolls the axes of which are inclined to the blank at such a large angle are of a very marked taper and short in proportion so that in fact they are flat discs. Corresponding 30 to the taper of the rolls, the taper of the mandrel is also very marked, and its face is as short as are the faces of the rolls.

With the axes of the rolls inclined at this large angle, it is difficult to accommodate the 35 driving mechanism and therefore mills of the type referred to could only be equipped with two rolls and required guiding means the provision of which involves further difficulties.

These drawbacks are overcome according 40 to my invention by reducing the angle which the axes of the rolls include with the axis of the blank. The maximum angle at which the axes of the rolls should be inclined is 30 degs., and a favorable angle is about 15 degs.

In a mill of this type the rolls have a slight taper only and are very long in consequence. The mandrel is long and slightly tapers in accordance with the rolls. Rolls of this kind can be supported in bearings at either end 50 and there is no difficulty to accommodate the driving mechanism so that three rolls may be provided instead of two, if desired.

One of the advantages obtained by a mill of this kind is that the forging of the blank 55 is much more favorable with respect to the expanding process. The very long and slightly tapering rolls in cooperation with a mandrel having the same properties, act on the blank with surfaces which are as long as 60 the rolls and the mandrel, but very narrow in the direction in which the rolls rotate. Such long and narrow surfaces practically 65 forge the blank exclusively at right angles to this longitudinal dimension. The forging surfaces rather resemble those of sheet-metal rolls. It is known that in such rolls there occurs no deformation in parallel relation to the longitudinal dimension of the forging 70 surface. In the present instance longitudinal expansion of the material in the axial direction of the tube is practically eliminated which is favorable with respect to the expansion of the tube and in connection with the process described in my copending applica- 75 tion.

Another very important advantage of my rolling mill with its slightly inclined rolls is that the feed-velocity can be considerably 80 increased as compared with the rolling mills hitherto designed. The time required for rolling a tube is a fraction of the time at present required which not only increases the output of the mill but also makes it comparatively independent from the gradual cooling 85 of the blank. The explanation is that in a rolling mill according to my invention, as compared with a mill of the type referred to, the section of the blank which is being forged at a time, is much larger. The effect is simi- 90

lar to that obtained by sub-dividing the last stages of a small-section rolling mill in order to increase the output of the mill. In the mill according to my invention the 5 length of tube which is being forged is increased, thereby also increasing the feed and the output.

The possibility of practically eliminating the temperature factor removes a serious 10 drawback inherent in the present system, to wit, its long rolling periods. The consequence of these long periods was that the temperature at the end of the tube, which was forged toward the close of the process, 15 was much lower than the initial temperature, which in turn caused irregularities in the wall thickness and the outside diameter, and, under certain conditions, even rendered the process impracticable. In my improved mill 20 the relation of the feeding and rotary components of the circumferential velocity of the rolls is different from that in normal rolls. This relation or, in other words, the direction of the circumferential velocity, is a function 25 of the distance between a given point of contact and the axis of the system, and the feeding component is increased by reducing this distance.

The advantage of providing bearings at 30 either end of the rolls is obvious, and the possibility of providing three rolls eliminates the necessity of providing guiding means, while an absolutely reliable centering of the 35 mandrel and a thoroughly uniform forging of the material by all rolls is guaranteed.

In the drawings affixed to this specification and forming part thereof a rolling mill embodying my invention is illustrated diagrammatically by way of example.

40 In the drawings

Fig. 1 is a plan view, and

Figs. 2 and 3 are sections on the lines II—II, and III—III in Fig. 1, respectively.

Referring now to the drawings, *p* are the 45 three rolls the axes of which are inclined to the axis of the blank at an angle not exceeding 30 degs. Each roll is supported in the housings *a* and *b* by means of spherical bearings *f* and *g*, respectively, *e* are spindles from which the rolls are driven by suitable knuckles *d*. *e* are foundations on which the 50 housings *a*, *b* are supported, *i* is a mandrel which is held by means of a socket *k* and a block *m*. *h* is the blank and *o* and *n* are channels for the 55 reception of the blank and the finished tube, respectively.

I wish it to be understood that I do not desire to be limited to the exact details of construction shown and described for obvious 60 modifications will occur to a person skilled in the art.

I claim:

65 A rolling mill for the expanding of blanks comprising long slightly tapered rolls, two bearings in and between which said rolls are

supported, the axes of said rolls being arranged at an angle not exceeding 30° to and in other planes than the axis of the blank, said rolls being so arranged with respect to the blank that the diameter of the rolls increases with the increasing diameter of the blank, and means for rotating said rolls so as to feed the blank through the mill in the direction from the small toward the large diameter of said rolls.

In testimony whereof I affix my signature.

FRITZ KOCKS.
